UNITED STATES PATENT OFFICE.

ALBERT SULLWOLD, OF GROVE, OKLAHOMA.

ANNUNCIATOR.

1,232,453.

Specification of Letters Patent.

Patented July 3, 1917.

Application filed October 4, 1915. Serial No. 54,008.

To all whom it may concern:

Be it known that I, ALBERT SULLWOLD, a citizen of the United States, residing at Grove, in the county of Delaware and State 5 of Oklahoma, have invented certain new and useful Improvements in Annunciators, of which the following is a specification, reference being had to the accompanying drawings.

10 This invention relates to certain improvements in annunciators and has relation more particularly to a device of this general character wherein an audible signal is employed; and an object of the invention is to provide 15 a device of this general character having novel and improved means whereby the operation is under thermostatic control.

Furthermore, it is an object of the invention to provide a device of this general character having novel and improved means whereby the same may be employed as a fire 20 alarm and whereby an alarm will be given upon the temperature adjacent the device reaching a predetermined degree.

25 It is also an object of the invention to provide a device of this general character wherein the signal is adapted to be electrically operated and wherein novel and improved means are employed including a trip bar 30 for normally holding the operating circuit open and whereby said trip bar is automatically operated to release a spring bar to close the operating circuit under predetermined conditions.

35 Furthermore, it is an object of the invention to provide a novel and improved annunciator wherein a plurality of signals may be arranged in parallel and whereby each 40 of the alarms may be cut out independently of the remainder of the alarms.

The invention consists in the details of construction and in the combination and arrangement of the several parts of my improved annunciator whereby certain important advantages are attained and the device 45 is rendered simpler, less expensive and otherwise more convenient and advantageous for use, all as will be hereinafter more fully set forth.

50 The novel features of the invention will be carefully defined in the appended claims.

In order that my invention may be the

better understood, I will now proceed to describe the same with reference to the accompanying drawings, wherein

55 Figure 1 is a diagrammatic view of an annunciator constructed in accordance with an embodiment of my invention;

Fig. 2 is a view in side elevation of a single device as included in my invention;

Fig. 3 is a view in top plan of the device as illustrated in Fig. 2, with the top or cover in an open position;

Fig. 4 is a sectional view taken substantially on the line 4-4 of Fig. 2; and

Fig. 5 is a view in elevation, detached, 65 of the trip bar as herein disclosed.

As disclosed in the accompanying drawings, 1 denotes a casing substantially rectangular in form and having its upper face 70 open, said upper face being adapted to be closed by the hinged top or cover 2, said top or cover being maintained in closed adjustment by the coacting locking members 3 of conventional construction.

75 One side of the casing 1 at an end thereof has secured thereto the block 4 to which is secured an extremity of the inwardly and longitudinally disposed spring bar 5 having secured to its free end the cross head 6 and 80 through the free extremities of which are disposed the contact members 7 and 8, the member 7 being in electrical connection with the spring bar 5 through the medium of the conductor *a* electrically connected with the 85 contact 7 and the plate 5.

The members 7 and 8 extend through and beyond the head 5 and coact, respectively, with the contact plates 9 and 10 and the anchored extremity of the spring bar 5 90 is in electrical connection through the medium of the conductor *b* with the center pole of the dry cell or battery *B* positioned within the casing 1. The contact 8 is also in electrical connection with the center pole 95 of the cell or battery *B* through the medium of the electrical conductor *c*, the contact plate 9 is in electrical connection through the medium of the conductor *d* with the signal or bell *S*, said bell being in electrical 100 connection with the side pole of the cell or battery *B* through the medium of the conductor *e*.

The contact plate 10 is in electrical con-

connection through the medium of the conductor *f* with the hanger 11 arranged at one end of the housing 1, while the second hanger 12 at the opposite end of the housing is in electrical connection with the side pole of the cell or battery B through the medium of the conductor *g*.

It will be perceived that upon the contact 7 engaging the plate 9 a circuit will 10 be closed through the conductors *d*, *e* and *b* to cause the signal or alarm *S* to operate. Engagement between the contacts 8 and 10 closes a circuit through the conductors *b*, *c*, *g*, *f* and the lines *L* with which the hangers 11 and 12 are electrically connected relative to the conductors *f*, *d*, *e* and *g* of the remaining devices in the event the switches *A* are in closed position as illustrated in Fig. 1.

It will also be self-evident that an individual 20 dual alarm may be cut out of the system by opening the switch *A* which coacts with each of the contact plates 9 and 10. As disclosed in Fig. 1, it will be perceived that should the contacts 7 and 8 at the bottom of 25 the sheet be caused to engage the plates 9 and 10 that the signal *S* of the first two devices will operate while the signal of the third device will remain silent as the switch *A* included therein is in open adjustment.

The spring bar 5 normally maintains the 30 contacts 7 and 8 out of engagement with the plates 9 and 10 through the medium of the trip bar 14 pivotally engaged, as at 15, with a block 16 secured to the side of the 35 casing 1 opposite to the block 4 and the trip bar 14 overlies the spring bar 5 and is provided with a notch 17 engageable with the bar 5 whereby the same is held in inoperative position.

Supported by the bracket 18 depending 40 from the casing 1 is the thermostatic wafer *W* of conventional form provided with an upstanding threaded member 19 with which is adjustably engaged the rod or post 20 45 which extends upwardly within the casing 2 and terminates directly beneath the trip bar 14. It will be perceived that upon the temperature immediately adjacent the wafer *W* reaching a predetermined degree, the expansion 50 of said wafer will elevate the rod or post 20 to cause said post or rod to engage the trip bar 14 and release the same from the spring bar 5 whereupon the contacts 7 and 8 carried by the head 6 will automatically 55 engage the plates 9 and 10 through the inherent resiliency possessed by the spring bar 5. When it is desired to reset the device, the spring bar 5 has connected therewith the rod 21 which extends exteriorly 60 of the casing 1 through a side thereof. As is believed to be self-evident, it is only necessary to force the rod 21 inwardly until the trip bar 14 is properly engaged with the spring bar 5, said trip bar 14 being

under the influence of the retractable member 22 which urges the trip bar 14 in a direction toward the spring bar 5.

From the foregoing description, it is thought to be obvious that an annunciator constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice.

I claim:

1. A circuit closer including a support, a block carried by the support, a spring bar secured to one end of the block and overlying the support, said spring bar being in communication with a source of supply, a head carried by the outer end of the spring bar at the side thereof and opposed to the support, a contact carried by the head and in electrical connection with the spring bar, a stationary contact carried by the support, a pivoted trip bar provided adjacent one end with a notch to receive the spring bar for holding the contact carried by the head of the spring bar out of engagement with the stationary contact, a thermostat carried by the support at the side thereof opposite to the trip bar and provided with a threaded member disposed in a direction toward the support, and a rod adjustably engaged with the threaded member and loosely disposed through the support and occupying the same plane as the trip bar and adapted to contact with the trip bar upon expansion of the thermostat for disengaging the trip bar from the spring bar.

2. A circuit closer including a support, a block carried by the support, a spring bar secured to one end of the block and overlying the support, said spring bar being in communication with a source of supply, a head carried by the outer end of the spring bar at the side thereof and opposed to the support, a contact carried by the head therethrough and in electrical connection with the spring bar, a stationary contact carried by the support, a pivoted trip bar provided adjacent one end with a notch to receive the spring bar for holding the contact carried by the head of the spring bar out of engagement with the stationary contact, means under thermostatic control for disengaging the trip bar from the spring bar, and a rod loosely disposed through the support and movable in the same general direction as

the spring bar, said member having its inner end secured to the spring bar whereby said spring bar may be moved into operative engagement with the trip bar and to dis-
5 engage the contact carried by the head of the trip bar out of engagement with the stationary contact.

In testimony whereof I hereunto affix my signature in the presence of two witnesses.

ALBERT SULLWOLD.
